(57) **CLAIM**

The ornamental design for a large capacity compost spreading and top dressing apparatus, as shown and described.

DESCRIPTION

FIG. 1 is a left side elevational view of the large capacity compost spreading and top dressing apparatus showing my new design, the apparatus being oriented in a position at which the apparatus is normally connected to a prime mover (not shown), a rear deflector member being shown in a raised position, optional front and rear hopper extension panels being shown in dotted lines;

FIG. 2 is a front elevational view of the large capacity compost spreading and top dressing apparatus shown in FIG. 1;

FIG. 3 is a right side elevational view of the large capacity compost spreading and top dressing apparatus shown in FIG. 1, optional front and rear hopper extension panels being shown in dotted lines;

FIG. 4 is a rear elevational view of the large capacity compost spreading and top dressing apparatus shown in FIGS. 1-3, optional rear hopper extension panel being shown in dotted lines;

FIG. 5 is a top plan view of the large capacity compost spreading and top dressing apparatus shown in FIGS. 1-4; and,

FIG. 6 is a left, rear perspective view of the large capacity compost spreading and top dressing apparatus shown in FIGS. 1-5 but with the rear deflector member being depicted in a lowered position.

The dotted lines are for illustrative purposes only and form no part of the claimed design.
